Primary Examiner — Rhea Shields(74) *Attorney, Agent, or Firm* — Ward and Smith, P.A.;
Ryan K. Simmons(57) **CLAIM**

The ornamental design for a closeable container, as shown and described.

DESCRIPTION

FIG. 1 is a perspective view of a closeable container showing a new design; and,

FIG. 2 is another perspective view of the closeable container of FIG. 1 showing an alternate configuration.

In the drawings, the broken lines are for the purpose of illustrating portions of the closeable container that form no part of the claimed design.
